UNITED STATES PATENT OFFICE.

CHARLES S. POWELL, OF ARDMORE, PENNSYLVANIA.

DESIGN FOR A BADGE.

SPECIFICATION forming part of Design No. 26,624, dated February 16, 1897.

Application filed July 9, 1896. Serial No. 598,610. Term of patent 7 years.

To all whom it may concern:

Be it known that I, CHARLES S. POWELL, a citizen of the United States, residing at Ardmore, county of Montgomery, and State of Pennsylvania, have invented and produced 5 a new and original Design for Badges, Pins, &c., of which the following is a full, clear, and exact description, reference being had to the accompanying drawing, which forms a 10 part of this specification.

The design, as illustrated in the drawing, consists, essentially, of the staff or holder A, having a flag of the shape and form shown in the drawing. The end of the flag attached 15 to the holder is of twisted form, (shown at B,) which apparently passes beyond the flag through and around the staff. There is a marginal effect *a*, which is preferably of the metal from which the badge or pin is formed. 20 The main body of the flag *b* is made of a solid

color, and upon the center of this ground is placed the monogram "U P," connected together as shown. As the design will be manufactured the ground *b* will be of a solid color, either red or blue, while the monogram will 25 be of the colors blue or red, that is, where the ground is blue the monogram will be red, and where the ground is red the monogram will be blue.

Having now fully described my invention, 30 what I claim, and desire to protect by Letters Patent, is—

The design for a badge or pin, substantially as shown and described.

In testimony of which invention I have 35 hereunto set my hand.

CHARLES S. POWELL.
